(57) **CLAIM**

The ornamental design for a cosmetic tool with rolling applicator, as shown and described.

DESCRIPTION

FIG. 1 is a right side elevational view of a cosmetic tool with rolling applicator showing the new design;

FIG. 2 is a left side elevational view of the embodiment illustrated in FIG. 1;

FIG. 3 is a front elevational view of the embodiment illustrated in FIG. 1;

FIG. 4 is a rear elevational view of the embodiment illustrated in FIG. 1; and,

FIG. 5 is top plan view of the embodiment illustrated in FIG. 1.

Surface shading is used to shade FIGS. 1-5 to show clearly the character and contour of all surfaces of the 3-dimensional aspects of the design and form a part of the design sought to be protected. The broken lines are for illustrative purposes only and form no part of the claimed design. The design shown is not to be limited to any particular size and may be scaled larger or smaller.
